US0D1076066S

(12) **United States Design Patent** (10) **Patent No.:** **US D1,076,066 S**
(45) **Date of Patent:** **** May 20, 2025**

(54) **ORAL IRRIGATOR**

(71) Applicant: **Aimi Health Technology (Guangdong) Co., Ltd**, Dongguan (CN)

(72) Inventor: **Yingjia Liu**, Dongguan (CN)

(**) Term: **15 Years**

(21) Appl. No.: **35/522,084**

(22) Filed: **Jul. 2, 2024**

(80) **Hague Agreement Data**

Int. Filing Date: **Jul. 2, 2024**

Int. Reg. No.: **DM/239226**

Int. Reg. Date: **Jul. 2, 2024**

Int. Reg. Pub. Date: **Aug. 23, 2024**

(57) **CLAIM**

The ornamental design for an oral irrigator, as shown and described.

DESCRIPTION

The patent or application file contains at least one drawing executed in color. Copies of this patent or patent application publication with color drawing(s) will be provided by the Office upon request and payment of the necessary fee.

1. Oral irrigator

1.1 : Front

1.2 : Back

1.3 : Top

1.4 : Bottom

1.5 : Left

1.6 : Right

1.7 : Perspective

1.8 : Perspective view of the state in use

1 Claim, 8 Drawing Sheets
(8 of 8 Drawing Sheet(s) Filed in Color)
